UNITED STATES PATENT OFFICE.

CHRISTIAN ROSS, OF CRIPPLE CREEK, COLORADO.

RAIL-BRACE.

No. 834,409.

Specification of Letters Patent.

Patented Oct. 30, 1906.

Application filed June 15, 1906. Serial No. 321,817.

To all whom it may concern:

Be it known that I, CHRISTIAN ROSS, a citizen of the United States, residing at Cripple Creek, in the county of Teller and State of Colorado, have invented a new and useful Rail-Brace; and I do hereby declare the following to be a full, clear, and exact description of the invention, such as will enable others skilled in the art to which it appertains to make and use the same.

The invention relates to clamps for railroad rails or tracks, and has for its object to provide a metallic clamp which will readily engage or disengage a pair of rails and easily adjust itself to the desired width of the track.

With these and other objects in view the invention consists in the novel construction and arrangement of parts hereinafter described and shown, and particularly pointed out in the appended claims.

In the drawings, Figure 1 is a side elevation of a clamp constructed in accordance with this invention. Fig. 2 is a plan view. Fig. 3 is a transverse sectional view taken on line 3.3 of Fig. 2.

Referring to the drawings, 1 designates the ends or members of the clamp, each having an integral jaw 2. The sections 1 are round and threaded at their inner end and are connected by a turnbuckle 3, by which the length of the clamp is adjusted as desired. The outer ends of sections or members 1 become rectangular in cross-section toward their outer ends and are provided with pivotally-mounted jaws 4, which lie on the upper faces of the members 1. The jaws 4 are each provided with U-shaped clamps 5, which are adapted to hold the jaws 4 against accidental rotation, thus preventing the said jaw from releasing the rail. The U-shaped clamps 5 are swung upward, which permit the jaw 4 to be rotated, which releases the rail.

In Fig. 3 is shown a transverse sectional view through one end of the turnbuckle, in which is illustrated the manner of locking the

turnbuckle at the desired adjustment. The turnbuckle is provided with an aperture in one end, through which a locking-pin 6 passes, which engages a flattened side of the member 1, as will be readily understood.

What I claim is—

1. A brace for railroad-rails, composed of two sections connected by a turnbuckle, each section having an outer integral jaw, an inner jaw co-operating with said integral jaw, said inner jaw being pivotally mounted on each of said sections, said inner jaw having a U-shaped clamp pivotally mounted thereon, for the purpose of holding the same against rotation.

2. A clamp having integral jaws, and pivoted jaws, said pivoted jaws, being capable of rotary motion, substantially as described.

3. A rail-brace having integral jaws, and pivotally-mounted jaws, and means, for holding said latter jaws, against rotation.

4. A rail-brace having integral jaws, and pivotally-mounted jaws, and a locking-device, for preventing movement of said last-named jaws.

5. A metallic rail-brace, composed of two sections, each section being adapted to engage railroad-rails, a screw-threaded turnbuckle, connecting said sections, said turnbuckle, having an aperture, and a pin mounted therein, and engaging a flattened side of one section, for locking the same in its adjusted position.

6. A rail-brace, having integral jaws, and pivotally-mounted jaws co-operating therewith, and a turnbuckle for adjusting said brace, and a locking-pin, mounted in said turnbuckle.

In testimony whereof I have signed my name to this specification in the presence of two subscribing witnesses.

CHRISTIAN ROSS.
